EXTENSION KEY CHAIN

Nathaniel N. Okun, Bronx, N. Y., assignor to
Swank Products, Inc., a corporation of Delaware

Application December 12, 1938, Serial No. 245,089

4 Claims. (Cl. 24—3)

This invention relates to a key chain and has for one of its objects to provide a key chain, the effective length of which may be extended.

Another object of the invention is to provide a key chain which will enable proper length to be had whether it be worn by a tall person or a short person.

Another object of the invention is to provide a key chain having two or more sections which will extend one along the other and will permit a relative adjustment to change the effective length of the key chain.

Another object of the invention is to provide a key chain having means for providing a simple manner for adjusting the length such as by pulling with a suitable force upon one length of the key chain and suitably holding another part thereof.

Another object of the invention is to provide a loop in the key chain to take up the length thereof and an adjustment of that loop for varying the effective length of the chain.

Another object of the invention is to provide a unit which will be fixed to one section of a key chain while it is slidable along another section of the key chain.

A further object of the invention is to provide in such a unit an arrangement whereby the sliding action may occur without scratching or abrading the chain.

With these and other objects in view, the invention consists of certain novel features of construction, as will be more fully described, and particularly pointed out in the appended claims.

35 In the accompanying drawing:

Fig. 1 is an elevational view illustrating a key chain with the key holder and garment attaching means assembled therewith;

Fig. 2 is a sectional view of a greatly enlarged scale of the unit whereby the adjustment of the chain may be accomplished;

Fig. 3 is a sectional view showing the jaws in full and the parts in position to receive the cover plate;

45 Fig. 4 is a sectional view of the device complete;

Fig. 5 is a top plan view of the outer casing;

Fig. 6 is a sectional view of the inner frame-like member within the casing; and

50 Fig. 7 is a sectional view of the jaws which frictionally grip the chain.

In the use of key chains it frequently occurs that the chain is either too long or too short, depending upon whether a tall or short person uses the same; also, it is often desirable to have a

longer or shorter chain, depending upon different objects which are to be unlocked with the keys upon the key holder which is attached to the chain. For instance, some persons may care to have a chain sufficiently long to enable keys to be attached by the chain and still extend to the dash of an automobile for the ignition thereof and after such use to again shorten the chain; and in order that this may be provided, I have formed two sections of chain which extend one along the other and which may be relatively adjusted by reason of a friction member on the end of one which is permanently attached to the other whereby an effective adjustment of the length of the chain may be provided; and the following is a more detailed description of the present embodiment of this invention, illustrating the preferred means by which these advantageous results may be accomplished:

With reference to the drawing: 10 designates a length of chain which has a key holder 11 with a key 12 thereon attached to one end thereof. To the opposite effective length of the chain there is provided a clip 13, or attaching member, to hook over the belt or upper edge of the trousers of the person wearing the same. The chain 10 passes through the ring 14 on the clip 13 for attachment thereto. In this particular instance, the chain 10 passes through the ring 14 and forms two sections 15 and 16 which extend one along the other.

These sections are attached together by means of a unit 17. One end of the section 15 is secured to the unit 17 as at 18, while the unit 17 is slideable along the section 16 to various positions so as to adjust the length of the overlying sections 15 and 16 which extend one along the other and thereby adjust the effective length of the chain, or the distance between the clip 13 and the key holder 11, may be shortened by sliding the unit 17 along the chain section 16 toward the key holder, while the distance between the key holder and the attachment 13 is lengthened or extended by sliding the unit 17 in the other direction or toward the attachment clip 13 and permitting the chain to slide through the loop 14 as the effective length of chain between the attachment 13 and the key holder 11 is changed.

The unit which is designated generally 17 consists of some friction jaw device which I term a 50 friction applying glide or easy grip glide for applying a slip grip or slip friction on one section of the chain but yet permitting it to slide through the unit when sufficient pull is exerted on the key holder to overcome such grip or the unit itself 55

may be slid along this section of the chain by manually gripping it and moving it outwardly from the trousers clip 13. The particular unit here illustrated consisting of a shell-like casing 5 20 consisting of a bottom wall 21 and peripheral side walls 22 with an inner frame-like member 23 conforming to the peripheral shape of the walls 22 and telescoping within them. This frame 23 is slotted as at 24, while the casing 10 is provided with an opening 25 through which the end 26' of the chain 10 may pass. The slot in the frame member is of a dimension to receive one of the links edgewise but would prevent the next link to it from passing through 15 the slot whereby to lock the chain in the unit. Within this casing and frame 23 is located a pair of jaws or glides 26 and 27, jaw or glide 26 being of a shape on its outer periphery 28 to conform to and fit snugly against the frame 23, while the jaw 27 has an outer periphery 29 to generally conform to the frame on the other side. An opening 30 is provided in the jaw 27 for the reception of coiled spring 31 which acts between the bottom of the bore 30 and the frame 23 to 20 force the jaw which engages the portion of the chain 16 which may pass through the unit by reason of the openings 32 and 33 in the walls 22 of the casing and similar openings 32' and 33' in the frame 23. A plate 34 extends across the frame 30 35 on one side and a similar plate 35 on the other side of the jaws forms a complete housing of the jaws, while a cover plate 36 may rest upon this inner plate 34 and a lip 37 may be rolled over the cover plate to hold the same in assembled position.

By reason of this arrangement which may have one or two units, such as 17, at one or both ends of sections 15 and 16, the chain may be adjusted for varying lengths of the effective distance between the hook or garment attaching part 13 and the holder 11.

While I have referred specifically to a key chain, this term may include any flexible member or cord for attachment or coupling of two parts together.

The foregoing description is directed solely toward the construction illustrated, but I desire it to be understood that I reserve the privilege of resorting to all the mechanical changes to which 50 the device is susceptible, the invention being defined and limited only by the terms of the appended claims.

I claim:

1. A device of the type described comprising an 55 article holding element, a flexible member having one end secured to said element with another portion extending back on itself to provide a loop, a unit containing within it friction applying glides between which the flexible member 60 extends to be slidable therealong, the other end of the flexible member being secured to said unit at a point spaced from the grip of the glides to permit a sufficient force tending to move the unit

along the member to overcome the applied friction of the unit to cause a change of the size of the loop, thereby causing change of the effective length of the flexible member.

2. A device of the type described comprising an 5 article holding element, an element for attachment to a part of wearing apparel, a flexible member having one end secured to one of said elements with another portion slidable through a part carried by the other of said elements and then extending back on itself to provide a loop, a unit containing within it friction applying glides between which the flexible member extends to be slidable therealong, the other end of the flexible member being secured to said unit at a point 15 spaced from the grip of the glides to permit a pull of a sufficient amount on the member tending to move the elements apart to overcome the friction applied by the unit to cause change of the size of the loop, thereby causing change of the effective 20 length of the flexible connection between said elements.

3. A device of the type described comprising an article holding element, an element for attachment to a part of wearing apparel to anchor the 25 same thereon, a flexible member having one end secured to one of said elements with another portion slidable through a part carried by the other of said elements and then extending back on itself to provide a loop, a unit secured to the other 30 end of the member and having a body with an opening through it through which opening the other portion of the loop of the member extends, means in the unit for frictionally gripping the through portion of said member with sufficient 35 pressure to maintain its position in normal use but permit sliding of the unit by a pull on the article holding element away from the anchor element for changing the effective length of the flexible connection between said elements. 40

4. A device of the type described comprising an article holding element, an element for attachment to a part of wearing apparel, a flexible member having one end secured to one of said elements with another portion slidable through a 45 part carried by the other of said elements and then extending back on itself to provide a loop, a unit secured to the other end of the member and having a body with an opening through it through which opening the other portion of the 50 loop of the member extends, the point of securing the said other end of the chain to the unit and the direction of the opening through the unit being so arranged that the through portion of the flexible member is but slightly out of alignment with the portions of the flexible member outside of the unit which it joins, means in the unit for frictionally gripping the through portion of said member with sufficient pressure to maintain its position in normal use but permit manual 55 sliding for changing the effective length of the flexible connection between said elements. 60
